ATTORNEY

UNITED STATES PATENT OFFICE.

DANIEL ROBERT BIZE, OF COLUMBUS, GEORGIA.

TRACE-CARRIER.

SPECIFICATION forming part of Letters Patent No. 289,211, dated November 27, 1883.

Application filed June 4, 1883. (No model.)

To all whom it may concern:

Be it known that I, DANIEL R. BIZE, a resident of the city of Columbus, county of Muscogee, and State of Georgia, have invented a certain new and useful Improvement in Back-Band Buckles; and I do hereby declare the following to be a full, clear, and correct description of the same, reference being had to the annexed drawings, making a part of this specification.

This invention relates to a buckle or slide having passages for a back-band, and spurs for engaging the same, an eye or half-ring for the passage of driving-reins, a hook for carrying the trace-chains, and a socket-ring for receiving the end of a belly-band or rope, whereby the harness is secured to the draft-animal.

In the accompanying drawings, Figure 1 is a perspective view of my improved buckle or clasp, and Fig. 2 represents the same as when applied to plow-harness.

The buckle or clasp consists of three parallel bars, *a b c*, having connecting end bars, *d e*. The central bar, *b*, is provided with spurs *f f'*, and the lower bar, *c*, with downwardly-projecting arms *g g'*, the lower ends of which are united and provided with an outwardly-projecting socket-ring, *i*, and at a short distance above the latter with a hook, as shown at *k*. The bars *a c* are connected at or about their centers with an outwardly-projecting band, forming a half-ring or eye, as shown at *l*.

In the application of my device one end of the back-band *M* is first passed from the rear through the space between the bars *a b*, then 35 around the latter, and back through the space between the same and the bar *c*, when it is pulled through to a sufficient extent to be securely held by the spurs, or the end can be folded back against the main part of the band 40 and then stitched or otherwise secured thereto. The belly-band *N* is passed through from the bottom of the socket-ring and a knot tied 45 therein to prevent its withdrawal from the same. The driving-reins *O* are passed through the half-ring or eye *l*, and the trace-chains *P* are supported, when desired, by the hook *k*.

Each set of harness is provided with a pair of my devices—one for each side thereof.

Having described my invention, what I claim 50 as new, and desire to secure by Letters Patent, is—

A plow-harness buckle or slide having bars *a b c* and spurs, for the purpose set forth, a half-ring or eye for the driving-reins, a hook 55 for carrying the trace-chains, and an outwardly-projecting socket-ring for securing the belly-band, substantially as specified.

In testimony whereof I affix my signature in presence of two witnesses.

DANIEL ROBERT BIZE.
